CLAIM

We claim the ornamental design for an adhesive bandage with decorated pad, as shown and described.

DESCRIPTION

FIG. 1 is a plan view of an adhesive bandage with a decorated absorbent pad showing my new design;
FIG. 2 is a side elevational view thereof, the opposite side elevational view being a mirror image;
FIG. 3 is an end elevational view thereof, the opposite end elevational view being a mirror image;
FIG. 4 is a plan view of a second embodiment of a decorated absorbent pad showing my new design;

FIG. 5 is a side elevational view thereof, the opposite side elevational view being a mirror image;

FIG. 6 is an end elevational view thereof, the opposite end elevational view being a mirror image;

FIG. 7 is a plan view of an adhesive bandage with a third embodiment of a decorated absorbent pad showing my new design;

FIG. 8 is a side elevational view thereof, the opposite side elevational view being a mirror image;

FIG. 9 is an end elevational view thereof, the opposite end elevational view being a mirror image;

FIG. 10 is a plan view of an adhesive bandage with a fourth embodiment of a decorated absorbent pad showing my new design;

FIG. 11 is a side elevational view thereof, the opposite side elevational view being a mirror image;

FIG. 12 is an end elevational view thereof, the opposite end elevational view being a mirror image;

FIG. 13 is a plan view of an adhesive bandage with a fifth embodiment of a decorated absorbent pad showing my new design;

FIG. 14 is a side elevational view thereof, the opposite side elevational view being a mirror image; and,

FIG. 15 is an end elevational view thereof, the opposite end elevational view being a mirror image.

The broken line showing of the backing of the adhesive bandage is included for the purpose of illustrating environment and forms no part of the claimed design.

The dashed lines are representative of boundaries between claimed and unclaimed subject matter in the embodiments of FIGS. 1-15. The jagged or wavy dot-dash lines in the unclaimed areas of the absorbent pad on either side of the claimed area of the absorbent pad in the embodiments of FIGS. 1-15 represent any portion of the article beyond what is shown forms no part of the claimed design.

The embodiment of FIGS. 7-9 illustrates a pattern that is similar to the pattern of FIGS. 1-3 but which is approximately two degrees off from vertical or from being parallel to the side edges of the absorbent pad. However, it will be appreciated that the orientation of the repeating pattern of the decorated absorbent pads of all embodiments of the present invention is intended to not be limited to be exactly vertical or parallel to the side edges of the absorbent pad.
